UNITED STATES PATENT OFFICE.

WILLIAM A. HOLMAN, OF PHILADELPHIA, PENNSYLVANIA.

DESIGN FOR A MOUNTING FOR BOOK OR ALBUM COVERS.

SPECIFICATION forming part of Design No. 26,231, dated October 27, 1896.

Application filed August 19, 1896. Serial No. 603,276. Term of patent 7 years.

To all whom it may concern:

Be it known that I, WILLIAM A. HOLMAN, a citizen of the United States, residing in the city of Philadelphia, State of Pennsylvania, have invented and produced a certain new and original Design for a Mounting for Book or Album Covers, of which the following is a full, clear, and exact description, reference being had to the accompanying drawings, forming 10 a part of this specification.

My invention relates to a mounting for book and album covers; and it consists in the novel form and configuration thereof, substantially as shown in the accompanying 15 drawings.

In the drawings, Figure 1 shows one of the mountings applied to a plush album-cover, a mirror (for illustration) being shown as held in place within the inwardly-curved edges or 20 flanges of the open center. Fig. 2 is an elevation of one of the mountings; and Fig. 3

is a section on the line 3 3, Fig. 2, showing the form and configuration of the frame of the mounting.

The design as shown in the drawings more 25 particularly consists in a mounting the frame of which has the general form of a harp. The inner edge of said frame is flanged or curved downward and inward, and its body portion is raised above the plane of its edges in what 30 may be called "alto-rilievo."

What I claim is—

The design for a mounting for book and album covers, substantially as herein shown and described.

In testimony whereof I have hereunto affixed my signature this 10th day of August, A. D. 1896.

WILLIAM A. HOLMAN.

Witnesses:

GEO. W. CLEMENT,
H. T. FENTON.
